UNITED STATES PATENT OFFICE.

JOSEPH HENRY RICKER, OF LOCK HAVEN, PENNSYLVANIA.

SECTIONAL BOILER.

SPECIFICATION forming part of Letters Patent No. 417,508, dated December 17, 1889.

Application filed August 31, 1889. Serial No. 322,512. (No model.)

To all whom it may concern:

Be it known that I, JOSEPH HENRY RICKER, a citizen of the United States, residing at Lock Haven, in the county of Clinton and State of Pennsylvania, have invented certain new and useful Improvements in Tube or Section Boilers; and I do hereby declare the following to be a full, clear, and exact description of the invention, such as will enable others skilled in the art to which it appertains to make and use the same.

The invention relates to improvements in tube steam-boilers; and its objects are to distribute the expansion of the tubes equally and prevent strain on the boiler-heads, to permit the boiler to be taken to pieces or dismantled very rapidly and easily and as easily put together again, so that it can be transported rapidly and with facility from place to place; to permit any tube to be separately detached and replaced or repaired as necessary, and to allow the boiler to be thoroughly and quickly blown off or flushed from the steam-dome downward.

The boiler, as hereinafter described, is of quite simple construction, very effective, and can be constructed cheaply.

In the accompanying drawings, in which similar letters of reference designate corresponding parts, Figure 1 represents a perspective of a tube-boiler resting on a furnace and embodying the invention. Fig. 2 is a side elevation thereof. Fig. 3 is an end elevation of the same. Fig. 4 is a detail longitudinal section of one end of a tube to show the securing-bolt and connected parts. Fig. 5 is a detail face view of one end of a tube. Fig. 6 is a detail perspective view of two pipes and the end sections to which they are attached, and illustrating the construction of the boiler. Fig. 7 is a detail in section of one of the sections of the head, the tube, and means for securing it in the head.

Referring to the drawings by letter, A designates the upper part of a furnace of any suitable construction, and B designates a tube-boiler embodying the invention superimposed on said furnace. The vertical end walls or heads C C' of said boiler are composed of the cells, steam chambers or sections c c', respectively, each of the inner of said sections having horizontal upper and lower

edges and parallel side edges inclined, as shown in Fig. 3, till near the said upper and lower edges, when said edges rise and descend vertically; but each of the outer of said sections has its outer edge vertical. This construction, as seen in the said figure, permits the sections to be placed together to form a rectangular wall. By this peculiar structure each section is of substantially the same size, and each one, though matched and closely fitted to is separate from the other ones adjacent. There is thus insured not only a peculiarly strong and compact structure, but a uniform and regular flow through the entire system of sections, heads, and tubes, &c. The sections, when in place, are bound together by the lower and upper manifold D D', respectively, at opposite ends, and the upper and lower cross-bars or supports d d', each of which is vertically opposite its manifold. The vertical tie-bolts E, which pass through the projecting ends of said manifolds and cross-bars, are secured by nuts e. In the arrangement of the manifolds and cross-bars I am governed by the number of horizontal rows of tubes. Where an uneven number is used, as in the drawings, the manifolds will come at opposite ends, and where an even number is used they will come at the same end. The position of the cross-bars will of course be changed in like manner.

F F are steam-boiler tubes extending between and connecting the chambered end walls C C', each section c c' having the adjacent ends of two of said tubes connected to and opening into it. The ends of the tubes are held in place by the following means: Each tube F has its ends rabbeted at f¹, so that one end fits into and abuts against a section-chamber c of one head and the other end in like manner fits into and abuts against a section c' of the head at the other end of the boiler, a metal gasket or packing f² fitting between the rabbeted end of each tube and its abutting section. Each tube end is provided with a circumferential standing rabbet f, Figs. 4 and 5, having the opposite notches f' cut in it, and depressions f² on a line on the inner face of said flange and at right angles to said notches. The flange f⁴ at the end of each tube insures

the snug fit of the tube in its appropriate hole c^2 in the section to which it belongs.

By having only two tubes enter each section there is secured a perfect and evenly-distributed circulation through the tubes, sections, &c., since there is but one inlet and one outlet for each section; and by this construction not only is a perfect and even circulation obtained throughout the entire structure, but in flushing or blowing off each tube and each section is sure to have the full force pass through it, so that the result attained is a complete cleansing of the boiler.

- 15 G is a T-shaped bolt having the shank g threaded at its outer end and the oppositely-standing arms $g' g'$ at its inner end. The said shank passes through openings in the walls of the adjacent chamber or section c or c' , and in a washer g^2 , preferably convex on its outer surface, and is engaged by a nut g^3 to the outer side of said washer, a suitable gasket or packing g^4 being interposed between the section and washer. In fitting the tube F in place the notches f' of the flange f are passed over the arms g' of the bolt, and the bolt is then given about a quarter-turn, so that the end of said arms will fall into the depressions f^2 , and the arms of the bolt will hold against the inner surface of the flange and the tube will bind against the section with which it communicates, the nut g^3 of course being turned up to make it bind as tight as desirable, the packing or gasket f^3 aiding to insure the proper tightness of the joint.

At any time when necessary for repair or other purpose any one or more of the sections of either head can be very easily and quickly removed and replaced. This feature of easy removal and replacement of the several parts of this boiler is one of very great value, rendering the boiler very serviceable and durable, as well as in the long run very cheap.

45 Each chamber or section c of the heads has the adjacent ends of two tubes F thus connected to it; but the opposite ends of the said two tubes are connected to different chambers or sections, so that any tube F may have both its ends detached, and may be removed from the boiler for any necessary purpose by detaching the washer, nut, &c., on the outside end of said tube and the gasket and washer at end of the other pipe in the same section, 50 when one pipe and one section can be removed, while the other section, to which it was connected, will be stayed by the remaining tubes. This is clearly illustrated in Fig. 6.

The upper row of tubes F have each one 60 end secured to the manifold D by the same means as the tubes are secured to the sections, their opposite ends being secured to the upper row of sections c' , while the lower row of tubes have each one end similarly secured to 65 the manifold D' and to one of the lower row of sections c .

H is the steam-dome, preferably in the form

of a horizontal drum or hollow cylinder and connected on the under side at its ends by pipe I to the center upper tube F and the 70 equalizing steam-pipes I' from the outer set of tubes which enter at the crown and above the water-line. In the drawings these pipes are shown at each end at the boiler—namely, the central connecting-pipe and the outside 75 equalizing-pipes. The discharge or blow-off cock Z' is shown at the lower end of the boiler.

In blowing off the proper cocks are opened and the water is forced from the dome through the manifold, heads, and pipes downward in 80 a zigzag flow, effectually removing with it all sediment, mud, and deposit of every kind.

The tubes F are preferably inclined slightly downward in the direction of the downflow of the stream in order that the latter may more 85 easily clean them.

It will be obvious to all skilled in the art to which this invention belongs that by means of this invention, as above described, the boiler can be made as large or as small as may be 90 desired by merely increasing or diminishing the number of sections in each head and tubes to correspond, because when the boiler is increased in size the added sections fit to and match with those already in, and when decreased in size the remaining sections will fit 95 and match together.

Having described my invention, I claim—

1. A sectional steam-boiler having its rectangular heads composed of independent closely-fitting sections or chambers, as described, combined and connected with tubes in such a manner that each section has two pipes connected with it, but which two at the opposite ends are connected with different 105 sections, whereby the flow upward or downward is regular and even through the entire system.

2. In a tubular steam-boiler, the combination of the heads C and C', respectively composed of the closely-fitting sections c c' , the connecting-tubes F, the dome H, and pipes connecting the same to the tubes, and the tie-rods E, manifolds D D', cross-pieces d d', and means for securing the sections and tubes 115 together, all in the manner and for the purposes set forth.

3. In a tubular steam-boiler, the combination of a drum-shaped steam-dome above the boiler, the end walls or heads composed of the closely-fitting sections, the tubes connecting the sections at opposite ends and intercommunicating from top to bottom through said sections, and the equalizing-pipes connecting the dome with the top tube of each 120 intercommunicating series of tubes and sections, substantially as specified.

4. In a steam-boiler, the combination, with the walled chamber or section forming part of an end wall or head, of a steam-tube rabbed at its ends and fitting into and against said chamber or section and provided with a circumferential inward-standing flange notched at opposite points, the T or bolt hav-

ing its shank threaded at the outer end and opposite arms to pass into said flange, and the nut to engage said threaded shank and bind the end of the tube against the section, substantially as specified.

5. In a sectional boiler, as described, the tubes each rabbeted at the end, also having instanding and notched flanges at the ends, combined with the head, and a T-bolt, washer, and gasket, and nut, whereby each pipe can be made steam-tight at the joint.

6. The combination of the pipes I', which enter the dome at its top or crown, with the tubes F and with the dome, in the manner and for the purposes set forth.

7. A tube-boiler having heads in sections matching and closely fitting together and united by manifolds and cross-bars and tie-bolts, and the tubes connecting said sections, 20 each having at each end an instanding flange

and held by T-bolt and nuts, washer, and gasket to the section, whereby the boiler can be readily taken apart, added to, or transported, substantially as described.

8. In a boiler, as described, the combination of the sectional heads with the manifolds D D' and cross-bars or supports d d', said manifolds and cross-bars arranged as shown and described, and the tie-bolts, the tubes, T-bolts, nuts, and washers, and gaskets, 25 30 as described, connecting said heads, whereby the boiler can be added to or reduced in size, substantially as specified.

In testimony whereof I affix my signature in presence of two witnesses.

JOSEPH HENRY RICKER.
